UNITED STATES PATENT OFFICE.

HIRAM LUCAS PIPER, OF MONTREAL, QUEBEC, CANADA.

SIGNAL LAMP.

Application filed April 23, 1926. Serial No. 104,220.

This invention relates to a railway signal lamp in which the colour screen carriers are adjustable enabling a green red or white light being displayed as desired, the adjustment being made from the exterior of the lamp shell, so that the same lamp construction can be used either as a marker or a classification lamp by a simple adjustment.

Heretofore the accommodation of the adjustable screen carrier of a signal lamp, within the shell of the lamp left such space between the shell and screens that leakage of white light from the lamp's source of illumination occurred around the edge of the screens with the result that the coloured light rays were dangerously neutralized. In order, therefore, to avoid this defect the present invention has been conceived with the object of so combining the lamp shell and adjustable screen that dangerous neutralization of coloured signal lights by the white illumination light is avoided, this object being specifically achieved by the provision of coloured screens curved in approximation of the arc of the movement of the carrier and contour of the lamp shell whereby such screens can be disposed in intimate association with the interior wall of the shell and so prevent leakage of white light outwardly around the screens in degree to avoid interference thereof with the coloured rays.

Further objects and advantages relating to generally improved construction including fitting of source of illumination and storage of extra coloured screens will be hereinafter more fully described in the specification and specifically pointed out in the appended claims.

For full comprehension, however, of my invention reference should be had to the accompanying drawings forming a part of this specification, in which the same reference characters indicate the same parts and wherein:

Fig. 1 is a vertical section through the shell of the lamp;

Fig. 2 is a top view of the lamp with the cover opened.

Referring now to the drawings, 2 indicates the cylindrical shell of my signal lamp, the lenses thereof being shown at 3 and the cover at 4.

The bottom 5 of the shell is centrally apertured at 6 to accommodate a coupling boss 7 which is fixed to the bottom by a flange 8 and extends upwardly and inwardly to con-

stitute a socket for an electric lamp 9 and downwardly and outwardly to constitute a coupling for a flexible sheath 10 enclosing electrical wires leading to the lamp socket. 60 This arrangement constitutes a simple and compact fitting for the source of illumination of the lamp and by avoiding side entrance of the wires eliminates side projections interfering with the positioning of the 65 lamp upon the railway car thus enabling the lamp being hung with the same facility as when illuminated by oil lamp contained entirely within the shell.

The lamp socket constitutes a pivot boss 70 for the adjustable screen carrier, this latter comprising a cylinder 11 dimensioned to snugly fit within the shell of the lamp and resting upon the shell bottom 5, and a bottom 12 centrally apertured to closely but 75 freely encircle the boss 7 and spaced upwardly from and paralleling the bottom 5 of the lamp shell. A spring clip 13 sprung into an annular groove 14 of the lamp socket boss retains the carrier cylinder in position 80 without resisting movement thereof around the boss.

A shallow cup-like disc 15 centrally apertured to snugly but freely encircle the lower projecting end of the boss 7 is pivotally supported upon the latter by means of a spring clip 16 sprung into an annular groove 17 in the boss. This disc carries a pin 18 extending upwardly through an arcuate slot 19 in the bottom 5 of the lamp shell and is 90 engaged with the carrier bottom 12 so as to impart rotary movement thereto without interfering with upward removal of the carrier cylinder when the clip 13 is removed. This engagement between pin 18 and carrier 95 is secured by passing the pin upwardly through the bottom 12. A handle or knob 20 fixed to the disc 15 enables same to be rotated and through it the carrier, the slot 19 being concentric with boss 7 and semi-circular in extent allowing the carrier to be rotated half way round within the lamp shell.

Secured to the bottom 5 are spring clips 21 with their free ends adjacent the ends of the slot 19 in position to snap over and yieldingly retain the pin 18 when it is carried to either end of the slot and thus prevent accidental displacement of the carrier, from adjusted position, through jolting of 110 the train and the like.

The carrier cylinder 11 is apertured at 22

in correspondence to the lensed apertures of the lamp shell so that the carrier apertures can be registered with the lenses. The bottom and side margins of the carrier apertures are provided with ledges or flanges 23 upon the interior of the carrier cylinder to constitute retaining slots for colour screens 24 which are slipped down or removed through the open top of the carrier cylinder. These screens are usually coloured sheets of glass and are curved correspondingly to the cylinder carrier and lamp shell so that with the screens upon the carrier the close association of the latter with the shell 10 is maintained across the aperture area. For this reason, coupled with the fact of the presence of the carrier in the form of a cylinder, the white illumination of the lamp 9 is retained within the cylinder without such 15 leakage as to interfere with the coloured rays produced by the screens.

It will be obvious that with coloured screens in position, a desired colour can be displayed through a lens of the lamp by 20 revolving the carrier through the medium of the exteriorly accessible knob 20.

Inasmuch as it is of advantage to provide a local store of screens for renewal of breakage, etc., I have utilized the space presented 25 within the dome-like cover 4 of the lamp for this purpose. Accordingly a pocket comprising a curved back 25 and inwardly overhanging side margins 26 is hinged as at 30 27 at one end of the interior of the cover and adapted to engage a spring latch 28 carried by the cover adjacent its opposite end. Spare screens are slipped between the back and overhanging margins and engaged by spring holders 29 carried upon the under- 35 side of the margins 26, these holders 29 and latch 28 holding the spares in place and preventing rattling thereof when the free end of the pocket is latched.

From the above it will be seen that a lamp 40 constructed in accordance with my invention will overcome the defect of interference with the coloured display by the white illuminating light and will present advantages in compactness and simplicity of construction 45 and facility of use.

What I claim is as follows:

1. In a signal lamp, the combination of a cylindrical lamp shell having light apertures; a cylindrical carrier within the shell and having light apertures adapted to register with the apertures of the shell; coloured screens upon the carrier and covering the apertures thereof; a tubular boss extending 50 upwardly and centrally through the bottom of the shell, the upper portion of the boss constituting a socket for an electric lamp; the said carrier having its bottom centrally apertured to closely but freely encircle the boss; an electric lamp carried by the socket end of the boss and the electrical wires

conducting current to the electric lamp extending upwardly from the exterior of the signal lamp through the boss to the socket end thereof; and means for rotating the carrier to bring the apertures thereof out of 55 or into register with the shell apertures.

2. In a signal lamp of the character described, having a shell and a dome shaped cover hinged to the shell, a pocket or holder for spare coloured screens located in said cover and hinged at one side to the cover and a spring latch on the cover to engage the opposite free side of the holder, said holder comprising a curved back and inwardly overhanging side portions each of 60 which has a spring holder mounted upon the inner side thereof.

3. In a signal lamp, the combination with a cylindrical lamp shell having light apertures in the sides and a curved slot in the bottom thereof, of a cylindrical carrier within the shell and having a bottom portion with a hole therein registering with the curved slot in the bottom of the shell and also having light apertures adapted to register with the apertures of the shell; coloured screens upon the carrier and covering the apertures thereof; a centrally located tubular boss secured to the bottom of the shell, which is apertured to accommodate it, extending downwardly therefrom and upwardly loosely through the apertured bottom of the carrier, the upper portion of the boss constituting a socket for an electric lamp; an electric lamp carried by the socket end of the boss and electrical wires conducting current to the electric lamp passing upwardly from the exterior of the signal lamp through the boss to the socket end thereof; a disc pivotally mounted upon the lower portion of the boss exteriorly of the shell, a pin carried by the disc and extending upwardly therefrom through the curved slot in the bottom of the shell into the registering hole in the bottom of the carrier and a knob upon the disc through the medium of which the disc is turned to move the carrier.

4. In a signal lamp, the combination with a cylindrical lamp shell having light apertures in the sides thereof and a curved slot in the bottom thereof, of a cylindrical carrier within the shell, and having a bottom portion with a hole therein registering with the circular slot in the bottom of the shell such carrier having light apertures adapted to 115 register with the apertures of the shell, coloured screens upon the carrier and covering the apertures thereof, a centrally located boss fastened to the bottom of the shell, extending downwardly therefrom and upwardly loosely through the bottom of the carrier, and presenting annular grooves near its top and bottom ends, an electric lamp fitted into the top of the boss, electrical wires passing upwardly through the boss, to the 120 125 130

lamp, from the bottom of the boss, a disc pivotally mounted upon the lower portion of the boss exteriorly of the shell, a pin carried by the disc and extending upwardly therefrom through the circular slot in the bottom of the shell into the registering hole in the bottom of the carrier and a knob upon the disc through the medium of which the disc

is turned to move the carrier, and spring clips in said grooves in the boss and bearing respectively against the exterior of the disc and the inner surface of the bottom of the carrier. 10

In testimony whereof, I have signed my name to this specification.

HIRAM LUCAS PIPER.
